AUTOMOBILE TENT

Theodore Heil, Lodi, Calif., assignor to Heilite Trailers,
Lodi, Calif., a limited partnership

Application August 12, 1957, Serial No. 47,316

Term of patent 14 years

(Cl. D14—6)

FIG. 1

FIG. 2

Fig. 1 is a rear perspective view of the automobile tent, embodying my new design.

Fig. 2 is a front perspective view of the same, but taken from the opposite side.

The portions of an automobile shown in broken lines are for purposes of illustration only.

I claim:

The ornamental design for an automobile tent, as shown and described.
